United States Patent Office.

JOHN J. NAYLOR, OF BRIGHTON, MICHIGAN.

Letters Patent No. 90,953, dated June 8, 1869.

IMPROVEMENT IN SEEDER AND FERTILIZER.

The Schedule referred to in these Letters Patent and making part of the same.

To whom it may concern:

Be it known that I, JOHN J. NAYLOR, of Brighton, in the county of Livingston, and State of Michigan, have invented a new and useful Improvement in Manure and Grain-Sowing Machines; and I do declare that the following is a true and accurate description thereof, reference being had to the accompanying drawings, and to the letters of reference marked thereon, and being a part of this specification.

Figure 1 is plan view of my invention, looking at the top.

Figure 2 is a cross-section on the line $x x$, fig. 1. Like letters indicate like parts in each figure.

The object of this invention is to construct a simple, cheap, and effective machine, for the purpose of sowing plaster, guano, bone-dust, or any other powdered manures, and grain.

In order to accomplish this end, I construct proper traction-wheels A, rigidly attached to the axle B, upon which is surmounted the frame O, by means of proper boxes, which allow the axle to rotate.

Upon this frame is secured the hopper D, within which revolves the cylinder E, provided with spurs F, for the purpose of keeping the contents in motion and preventing the same from packing and clogging up the mouth of the hopper.

This cylinder is rigidly attached to the shaft H, the ends of which project through the ends of the hopper, and are provided with pulleys I, around which, and suitable pulleys J on the axle, pass the belts K, by means of which the cylinder is rotated.

The hopper is provided with a suitable opening, L, and gate M, through which the contents pass into the conductor N, which leads from the hopper to the distributing-box O.

This box is attached to the rear of the frame O, and is provided with cylinder P, which is furnished with spurs Q, and is properly journalled into the ends of the box, which is also provided with a conveyer, R,

whose periphery is provided with spiral flanges or threads, so arranged as to convey the contents of the box, which are received through the conductor N, even to the ends of said box, whence they are distributed upon the ground through apertures S, in the bottom of box O.

The cylinder P and conveyer R are both journalled into the ends of the box O, and at one end are provided with geared wheel T, on the end of the conveyer, and pinion U, on the end of the cylinder P, to which motion is given by the geared wheel V, which is rigidly attached to shaft W, suspended in proper bearings X, and driven by means of belt Y, from pulley Z, on the axle.

A" is an oscillating slide secured under the bottom of the box O, in such a manner that it can readily be adjusted by means of the lever B", and is provided with a series of openings, corresponding with the openings in the bottom of the box O.

By means of this slide, the amount of grain, or other material to be sown, can very easily be determined.

Having thus explained the construction of my device, which is very simple, I deem it unnecessary to further explain its operation.

What I claim as my invention, and desire to secure by Letters Patent, is—

The construction of an apparatus combining the wheels A, axles B, frame C, hopper D, cylinder E, spurs F, shaft H, pulleys I and J, belts K, gate M, conductor N, distributing-box O, cylinder P, conveyer R, geared wheels T and V, pinion U, shaft W, bearings X, belt Y, pulley Z, slide A", and lever B", when arranged and operating, substantially as and for the purposes herein set forth and shown:

JOHN J. NAYLOR.
